UNITED STATES PATENT OFFICE.

HOWE E. DANTZEBECHER, OF PHILADELPHIA, PENNSYLVANIA.

DESIGN FOR A KITE-FRAME.

SPECIFICATION forming part of Design No. 28,905, dated June 21, 1898.

Application filed March 22, 1898. Serial No. 674,840. Term of patent 7 years.

To all whom it may concern:

Be it known that I, HOWE E. DANTZEBECHER, a citizen of the United States, residing at Philadelphia, county of Philadelphia, 5 and State of Pennsylvania, have invented and produced a new and original Design for Kite-Frames, of which the following is a specification, reference being had to the accompanying drawings, showing a part thereof.

Figure 1 is a front view of a kite, showing my design. Fig. 2 is a back view, and Fig. 3 is longitudinal sectional view.

The leading features of my design consist of a frame having the general outline of a 15 man standing akimbo, which appears when viewing the kite from the rear, and depending from the center base, on which the feet are fixed, is a rod having arranged thereon a rudder-like wind-blade.

A is the frame of the kite of the outline 20 shown in Fig. 2, and B represents the material

stretched upon said frame to form the kite, which presents upon the face thereof the representation of "Uncle Sam," while beneath the feet of this picture extends a slim rod C, 25 carrying a wind-blade D, which is of the shape shown in Fig. 3. The cords E, which also form a part of the frame, are so arranged as to inclose a triangular space, which gives the appearance of a base upon which "Uncle 30 Sam" is standing.

What I claim is—

The design for a kite-frame as herein shown and described.

In testimony whereof I have hereunto affixed my signature in the presence of two subscribing witnesses.

HOWE E. DANTZEBECHER.
